ART OF COKING HYDROCARBONS

Harry L. Pelzer, Houston, Tex., assignor to Sinclair Refining Company, New York, N. Y., a corporation of Maine

Application May 1, 1931, Serial No. 534,285

3 Claims. (Cl. 196—107)

This invention relates to improvements in systems for carrying out the combined vapor phase cracking of oils, such as gas oil or kerosene stocks, for the production of lower boiling oils, such as gasoline, and the coking of heavy oils, such as crudes, topped crudes, flux oils, and other residual stocks and the like, by passing the hot vapor mixture from a vapor phase cracking operation, while still at high temperature, in intimate contact with a liquid oil mixture to be reduced to coke in a receptacle adapted to receive an accumulating charge of coke thereby coking this liquid oil mixture by the heat of the hot vapor mixture from the vapor phase cracking operation.

The operation described in my application filed February 19, 1929, Serial No. 341,214, is an example of such operations.

The vapor mixtures from vapor phase cracking operations are peculiarly difficult to handle prior to the separation of the tarry constituents which they normally contain as discharged, at temperatures upwards of 950° F., from the vapor phase cracking operation proper. Characteristically these tarry constituents of such vapor mixtures tend to form deposits choking or plugging any stagnant spaces in lines or valves. The usual T connection to two gate valves to connect one line to either of two other lines, for example, even where the legs of the T are very short and are connected directly to the gate valves, is not satisfactory for this purpose because, with the vapor mixture passing through either of the alternate passages, a deposit tends to form in the stagnant leg of the T rendering the operation of the valve system uncertain and irregular.

Two-way valves embodying plug-type closure members assist in the elimination of stagnant regions but in such service such valves tend to "freeze" in one position or to become locked in one position due to the development of "bridges" of hard coke between the closure member and the valve body. This invention relates particularly to improvements minimizing such difficulties when such valves are embodied in systems for carrying out such operations.

A system embodying the invention is illustrated, diagrammatically and conventionally, in Fig. 3 of the accompanying drawing, and details of the two-way valves embodied in this system are illustrated in Figs. 1 and 2, Fig. 1 being a section through the axis of the closure member of the valve and Fig. 2 being a section on line 2—2 of Fig. 1.

Referring to Fig. 3 of the drawing, the system

illustrated may be operated as described in my application Serial No. 341,214, previously mentioned, the connections 16 and 7 and the receptacles A, B, C and D corresponding to the connections and receptacles so designated in that application. The two-way valves in this system are shown in position to permit flow from the heater through connection 16 through receptacles B and C in succession to connection 7. To establish flow through receptacles C and D in succession, for example, two-way valves 20 and 21 are first reversed and two-way valves 22 and 23 are then reversed. A similar operation establishes flow through receptacles D and A in succession, through receptacles A and B in succession and so on.

These two-way valves, illustrated in detail in Figs. 1 and 2, comprise a frusto-conical rotatable plug 4 seated in a body 5. The body 5 is provided with three ports, 6, 7 and 8; and the plug 4 is provided with two communicating ports 9 and 10 arranged so that by rotation of the plug port 8 can be connected either to port 6 or to port 7. A chamber 11 in the body 5, not in communication with any of the passages through the valve body and plug just described or the connections thereto, is closed on one side by the smaller end of the plug 4. A valved connection 12 is provided through which relatively cool oil may be supplied to chamber 11 under pressure sufficient to lift the plug 4 free from its seat in the body 5. The connection 12 enters directly the chamber 11, without passing through plug 4 or through more than a minimum of the body 5, so that oil supplied through this connection is subjected for a minimum period of time to the temperatures prevailing in the valve. Set screws 13, 14, 15, etc., are provided to assist in positioning and in maintaining in position the plug 4. To maintain the plug in position set screw 13 is withdrawn from engagement with the plug 4 and set screws 14 and 15, etc., are forced against the plug 4; to assist in releasing the plug 4 set screws 14 and 15, etc., are withdrawn from engagement with the plug 4 and set screw 13 is forced against the plug 4.

Again referring to Fig. 3, immediately in advance of each of the two-way valves on the entrance side of the coking receptacles, in connection 24 with respect to valve 22 for example, an auxiliary valved connection, 25 for example, is advantageously provided for the introduction of relatively cool oil into the vapor mixture entering the valve. Similar auxiliary connections may be provided in advance of the valves on the

discharge side of the coking receptacles, valve 20 for example, but their provision is less important at this point.

The operation of the invention as embodied 5 in the system illustrated in Fig. 3 will be illustrated by specific reference to the operation of valve 22. Assume a mixture of oil vapors at a 10 temperature of 1000-1020° F. flowing from the heater through connections 16 and 24, through 15 valve 22 and through connections 26 and 27 to the coking receptacle B, set screw 13 being loose and set screws 14 and 15 being tight and valved 20 connections 12 and 25 being closed, to reverse the position of the valve 22 so that the vapor mixture will pass through connection 28 instead of 25 connection 26, the set screws 14 and 15 are loosened and the set screw 13 is tightened, cool oil, gas oil for example at a temperature of 60-80° F. for example, is forced under pressure 500-1500 30 pounds per square inch for example, through connection 12 into chamber 11 and, advantageously, the introduction of cool oil, of similar character and at a similar temperature for example, through connection 25 is initiated. The oil supplied to the chamber beneath the plug operates 35 to lift the plug from its seat in the valve body and, as the plug is lifted from its seat in the valve body, to cool and lubricate the plug and seat. The oil introduced through connection 25 is vaporized thus cooling the vapor mixture by the 40 absorption of both sensible heat and latent heat of vaporization. The oil so introduced thus assists in cooling the valve and, to the extent that this cooling is abrupt, assists in freeing the valve 45 plug from its seat. Gas oil or similar oil introduced into the system through connection 25 or flowing into the system from the chamber 11 between the valve plug and its seat in the body of the valve joins the oil undergoing treatment in 50 the system. As soon as the valve plug is free, it is rotated to the desired position, valved connections 25 and 12 are closed, set screw 13 is loosened, and the set screws 14 and 15, etc., are tightened.

By introducing cool oil immediately in advance 45 of the two-way valves just before changing their position in sufficient volume to cool them quickly over a substantial range of temperature, the valve plug may be freed from its seat in some operations without requiring the application of fluid 50 pressure beneath the smaller end of the valve plug.

I claim:

1. In a system for reducing heavy oils to coke comprising a heater in which oil is heated to a cracking temperature upwards of 950° F., a coking receptacle adapted to permit the reduction of heavy oil to coke therein by the heat of the hot oil products discharged from said heater and a connection for discharging such hot oil products from said heater into said coking receptacle, a valve positioned in said connection comprising a 10 frustro-conical rotatable plug seated in a body provided with ports communicating with said connection, a chamber not in communication with said ports or said connection and closed on one side by the smaller end of said plug when and 15 only when said plug is seated, and means for supplying relatively cool oil to said chamber under pressure.

2. In a system for reducing heavy oils to coke comprising a heater in which oil is heated to a 20 cracking temperature upwards of 950° F., a coking receptacle adapted to permit the reduction of heavy oil to coke therein by the heat of the hot oil products discharged from said heater and a connection for discharging such hot oil products from said heater into said coking receptacle, a valve positioned in said connection comprising a frustro-conical rotatable plug seated in a body provided with ports communicating with said connection, a chamber not in communication with 25 said ports or said connection and closed on one side by the smaller end of said plug, means for supplying relatively cool oil to said chamber under pressure, and means for introducing relatively cool oil into said connection immediately in 30 advance of said valve.

3. In a system for reducing heavy oils to coke comprising a heater in which oil is heated to a cracking temperature upwards of 950° F., a coking receptacle adapted to permit the reduction of heavy oil to coke therein by the heat of the hot oil products discharged from said heater and a connection for discharging such hot oil products from said heater into said coking receptacle, a valve positioned in said connection comprising a frustro-conical rotatable plug seated in a body provided with ports communicating with said connection, and means for introducing relatively cool oil into said connection immediately in 45 advance of said valve.

HARRY L. PELZER.
